CHECK CONTROLLED MECHANISM

Fairfield W. Hoban, New York, N. Y., assignor to
 Stewart and McGuire, Incorporated, New York,
 N. Y., a corporation of New York

Application December 28, 1935, Serial No. 56,558

9 Claims. (Cl. 194—63)

My invention relates to improvements in check controlled mechanism for vending machines or the like, and the same has for its object to provide a simple, reliable and efficient mechanism which is responsive to coins of different denominations for dispensing merchandise corresponding in quantity with the value of the coin employed.

Further, said invention has for its object to provide a mechanism of the character specified in which the operating means thereof, when released by the coin, is capable of being rotated a step or through a succession of steps in the same direction according to the value of the coin inserted.

Further, said invention has for its object to provide a mechanism of the character specified in which the operating means thereof, when controlled by the coin of greater value, requires rotation through a single revolution only to dispense merchandise of corresponding value.

Further, said invention has for its object to provide a mechanism of the character specified in which the coin released interlocking parts thereof are co-ordinated to allow limited movement of the actuator at each locking position for the purpose of operating a scavenger, a fraud preventing device, or other means employed with or in the apparatus.

Further, said invention has for its object to provide a mechanism of the character specified in which the operating means thereof is duly centered in each of the successive locking positions of the mechanism to insure proper operation thereof.

Further, said invention has for its object to provide a mechanism of the character specified in which means are included for insuring full quantity delivery of merchandise from the delivery pockets of the operating means when the same is rotated through a complete revolution upon release thereof by the coin of greater value.

Other objects will in part be obvious, and in part be pointed out hereinafter.

To the attainment of the aforesaid objects and ends, my invention consists in the novel features of construction, and in the combination, connection and arrangement of parts hereinafter more fully described and then pointed out in the claims.

In the accompanying drawings:

Figure 1 is a longitudinal sectional elevation of one form of apparatus constructed in accordance with and embodying my said invention;

Fig. 2 is plan thereof on a plane below the hopper and a scavenger which are removed;

Fig. 3 is transverse elevation of a movement interrupting means having a portion broken away and in section, said view being taken on the line 3—3 Fig. 2 looking in the direction of the arrows;

Fig. 4 is a transverse view of the front of the check controlled mechanism with parts broken away, said view being taken on the line 4—4 of Fig. 1 looking in the direction of the arrows;

Fig. 5 is a corresponding view illustrating the limited movement thereof for controlling a scavenger;

Fig. 6 is a transverse sectional view of said mechanism taken on the line 6—6 of Fig. 1 looking in the direction of the arrows;

Fig. 7 is a detail section view showing a slip connection between two members of the mechanism and taken on the line 7—7 of Fig. 6 looking in the direction of the arrows;

Fig. 8 is a transverse section view taken on the line 8—8 of Fig. 1 and illustrating the scavenger in elevation in full;

Fig. 9 is a transverse section of the mechanism through the coin carrying pockets thereof taken on the line 9—9 of Fig. 2; a coin being shown in position therein;

Fig. 10 is a corresponding view with parts broken away and in section, said mechanism being slightly displaced clockwise to illustrate the operation when employing a cent coin as the detent actuator;

Fig. 11 is a similar view illustrating the operation when employing a five cent coin as the actuator;

Fig. 12 is a transverse sectional view through the dispensing drum or rotor on the line 12—12 of Fig. 2 looking in the direction of the arrows;

Fig. 13 is a rear transverse elevation of the coin controlled mechanism looking at the rear thereof; and

Fig. 14 is a perspective of the apparatus suitably encased.

Referring to the drawings, the coin controlled mechanism 10 is shown applied to an encased vending machine (Fig. 14) for dispensing or delivering merchandise, such as candy, nuts or similar articles in loose form and in measured quantities in accordance with the value of the coin inserted. The apparatus controlled by the mechanism 10 comprises rotatable means 11 including a carrier or drum 12 mounted for rotation about a horizontal axis below the open discharge end of a hopper 13 for receiving the com-

modity, the drum 12 being provided with pockets 14 adapted to successively register with the hopper for receiving the commodity therefrom. The drum 12 is preferably secured for rotation upon suitable shafting 15 having a bearing 16 at the front in a support or bridge 17 and having a bearing 18 at the rear thereof in a suitable support 19, preferably the rear wall of the casing 20 (Fig. 14) employed to enclose the mechanism or apparatus. The shafting 15 has an actuating member or knob 21 at the front end thereof adapted to be rotated in a clockwise direction.

To facilitate the assembly of the apparatus within the casing 20, and its removal therefrom, the shafting 15 preferably consists of aligned sections 22 and 23 while the drum 12 carried thereby preferably consists of two telescoping sections 24 and 25 in adjustable sliding engagement with each other to allow adjustment of the size of the pockets. The forward shaft section 22 carries the coin controlled mechanism 10 and is rotatably supported in the bridging member 17 and retained against axial movement therein by said mechanism 10 and the knob 21. The rear end 26 of the shaft section 22 receives the forward section 24 of the drum 12 which is provided for this purpose with an axial socket or opening 27 closed at its rear end by the shaft section 23 forming a stop 28 engaging the end of the section 22 whereby to locate the drum section 24 in proper relation to the hopper 13. The shaft portion 26 and drum section 24 are keyed to each other against relative rotation by suitable means, such as the flats 29.

35 By the construction above described, the shaft section 22 together with the mechanism and parts disposed thereon may be readily disengaged from the drum section 24 and withdrawn from the casing of the vending machine.

40 The rear drum section 25 interfits the front drum 24 in complementary relation thereto and is provided with an axial collar 30 at the rear thereof adapted to receive the forward end of the shaft section 23 which is journaled at its 45 rear end in the bearing 18. The drum section 25 is capable of being slid along the shaft section 23 to vary the length of the pockets 14 and is secured in any adjusted position by means of the set screws 31.

50 The hopper 13 is supported as usual within the casing 20 in depending relation to the commodity reservoir 32. The intermediate portion of the operating means or shafting 15 is also preferably supported by a member or hanger 33 attached to the hopper 13 and depending therefrom, said member 33 having an annular end portion 34 receiving the collar 35 formed on the forward end of the drum 14.

55 In the embodiment of the invention disclosed herein the lower end of the hopper 13 is arcuately shaped to correspond in outline with that of the drum 14 which interfits the same. As shown in Figs. 1 and 12, the lateral wall of the hopper at the side towards which the drum rotates at its 60 lower end has a clearance or opening 36 therein closed by spring members or gates 37 which wipe over the periphery of the drum as the successive pockets 14 are brought into discharging relation to the lateral chute 38 supported by the 65 bridge or frame 17 for delivering the commodity to the purchaser. The gates 37 prevent clogging or jamming during rotation of the drum because of the projection of pieces of the commodity above the drum, and cause excess pieces of the commodity to be swept back into the hopper,

Efficiency in the operation of the drum is also enhanced by the provision of means 39 within the hopper 13 contiguous to the drum 14 and directly in advance of the gates 37 for yieldably holding the head of nuts or other commodity 5 within the hopper from crowding against the gates, and thus interfering with the discharging operation. Such means 39 preferably consists of a coil spring stretched across the hopper in advance of the gates and secured at the ends to 10 suitable brackets 40 upon the hopper.

The coin controlled mechanism 10 preferably comprises an intermediate integrally formed member 41 including a ratchet element 42 having a succession of steps 43 thereon corresponding in number with the maximum number of coin units for which the apparatus is adapted. The member 41 also includes an axial sleeve 44 having oppositely projecting hub portions 45 and 46 adapted to receive the shaft 22 upon which 20 the member is mounted.

The coin controlled mechanism also includes means 47 for properly centering the same in the successive locking positions. Such means preferably includes a centering portion 48 formed upon 25 the front face of the ratchet element 42 including a succession of recesses 49 corresponding in number with the number of steps 43 on the ratchet 42 and arranged in corresponding relation to said steps. The centering element 48 co-operates with a dog 50 pivoted at 51 to the frame member 17 and provided with a coil spring 52 for retaining the same yielding engagement with the successive recesses 49. The recesses 49 and the nose 53 of the dog 50 are preferably of complementary arcuate 30 contour, the interengaging arcuate portions having a camming relation to insure the proper positioning of the parts in centered positions as the mechanism is rotated clockwise through the successive steps or positions thereof and to insure 35 return to centered position upon a partial or incomplete movement in a clockwise direction as hereinafter more fully described.

The forward hub 45 is adapted for the mounting of a forward member or element 54 of the control 45 mechanism 10. Such element 54 is provided with an axial opening 55 therein for receiving the hub 45 and includes a disk portion 56 having coin receiving pockets 57 formed upon the rear face thereof. The pockets 57 are of arcuate formation adapted to receive and hold therein coins of various denominations, such as a one cent piece or a five cent piece (a nickel). The pockets 57 correspond in number with the number of successive locking positions of the mechanism and are 50 disposed in predetermined relation to the successive centering positions to allow the coins to drop vertically into the same by gravity and to discharge any coin therein upon movement of the actuator a complete step in a clockwise direction. 60

The forward face of the member 54 has formed thereon a ratchet portion or element 58 co-operating with a detent 59 for preventing rotation of the mechanism in a counter-clockwise direction. The detent 59 is preferably pivotally mounted at 65 60 to the frame member 17 coaxially with the pivot 51 of the dog 50, and is retained in engaging relation with the ratchet 58 by the spring 61. The ratchet 58 is provided with more steps or teeth 62 than the ratchet 42 has, the teeth relationship being three to one in the embodiment of the invention illustrated, to allow rotation of the actuator in a clockwise direction a part of a 70 complete step without the detent 59 dropping into the next succeeding dwell of the ratchet 58, for 75

a purpose hereinafter described.

The control members 41 and 54 are preferably separated by an intervening disk 63 threaded upon the hub 45 and serving as a common wall for the centering recesses 49 and coin pockets 57.

The members 54 and 63 are preferably keyed to or interlocked with the intermediate member 42 by forming lugs 64 upon the hub 45 adapted to be received into corresponding slots or recesses 65 and 66 formed in the member 54 and member 63 respectively.

Another member or disk 67, provided with an axial opening 68 for receiving the hub 46, is rotatably mounted upon said hub against the rear face of the intermediate member 41. The member 67 is of relatively greater diameter than that of the ratchet 42 and is provided with a notch or clearance 69 in the periphery 70 thereof for receiving the offset nose 71 of a coin actuated member or detent 72 co-operating with the ratchet 42.

The detent 72 is pivoted at 73 to the frame member 17 at the side thereof opposite the dog 50 and detent 59 in position to engage the ratchet 42 and to lie in operative relation to the coins moved into camming relation thereto when the operating means is rotated with a coin in any pocket thereof. The detent 72 is retained in engagement with the ratchet 42 by the spring 74, and is provided with an intermediate step or abutment 75 on the lower edge thereof adapted to engage and ride upon the dwells 76 of the ratchet 42 intermediate the teeth 43 as shown in Figs. 4 and 6 illustrating the mechanism 10 in normal or centered position. In the normal position of the mechanism the abutment 75 engages an intermediate portion of the dwell 76 to allow a limited or slight rotation of the mechanism in a clockwise direction and return before the abutment 75 engages the next succeeding step of the ratchet 42, as shown in Fig. 5. In the position of Fig. 5 the detent 59 assumes a position at the extreme edge of its step without disengaging the same to allow of the parts to be returned to normal or centered position by means of the centering spring 52. The detent 72 has a laterally projecting pin 77 extending transversely over the coin receiving means 56 in position to be actuated by the coins therein as illustrated in Figs. 9 to 11 and herein-after described.

The disk member 67 is retained in position upon the hub 46 by means of the sleeve or retaining member 78 secured to the hub 46 and shaft 22 by the transverse pin 79 which also serves to secure the member 41 against rotation relative to the shaft 22.

The disk member 67 serves as means for supporting the detent 72 disengaged from the ratchet 42 to allow a complete revolution of the operating means when the detent is actuated by a coin of greater diameter, such as the nickel, the periphery 70 of said disk 67 serving as a dwell upon which the nose 71 of the detent rides during said revolution. Said detent 72 disengages said dwell 70 and drops into the clearance space 69 at the completion of the revolution to again engage the ratchet 42 and lock the mechanism.

For this purpose, the disk 67 has a yieldable slip connection 80 with the member 41 to allow the member 67 to rotate with the operating means when the detent is actuated to clear said member, and to allow relative movement of the operating means when the detent 72 is actuated by a coin of lesser diameter, such as a cent piece, to clear the ratchet 42 but not the disk 67.

The slip connection 80 is such as to lock the

disk 67 to the member 41 in a succession of relative positions corresponding in number with the ratchet steps 43. As shown, the ratchet member 42 upon the back face thereof is provided with a series of recesses 81 disposed in corresponding relation to the steps 43 while the disk 67 has an opening 82 therein adapted to register with the recesses 81 in the successive positions. The opening 82 receives a locking element 83 retained in place by a leaf spring 84 and adapted to enter the successive recesses 81 to lock the parts together for joint rotation.

As shown in Fig. 5 the clearance space 69 is sized to allow in each of the locking positions of the disk 67 limited movement of the operating means in a clockwise direction and return without the nose 71 of the detent 72 engaging the abutment 85 at the end of the clearance space. The successive locking positions of the slip connection 80 are located to lock the disk 67 to ratchet 42 with said abutment 85 in the same position relative to the successive locking steps or positions. When the detent 72 is elevated by a coin of smaller diameter upon rotation of the operating means, the nose 71 of the detent engages the abutment 85 to disengage the slip connection 80 and retain the disk 67 against movement with the operating means, the parts relatively moving to interlock in the next succeeding relative position thereof ready for operation upon insertion of another coin.

The coins for releasing the mechanism 10 are preferably delivered thereto through a fraud preventing device or scavenger 86 (Figs. 1 and 8) secured to the frame member 17 in position above the coin pockets 57 for removal with the control mechanism 10. The device 86 preferably comprises a fixed front plate 87 secured to the frame member by a screw 88 and a movable plate 89 at the rear thereof pivoted at its upper edge to the fixed plate at the upper edge thereof, as indicated at 90. The single scavenger 86 controls the passage of both the cent and nickel to the control mechanism 10 and measures the dimensions thereof and weighs the same. For this purpose, one side 91 thereof serves for the passage of the cent piece and the other side 92 thereof serves for the passage of the nickel.

The cent is inserted into the machine through the slot 93 (Fig. 14) which registers with an opening 94 at one side of the scavenger and the nickel is inserted through a slot 95 (Fig. 14) which registers with an opening 96 at the opposite side of the scavenger. The passages 97 and 98 formed between the plates 87 and 89 are dimensioned to correspond with the diameters and thicknesses of the respective coins. The cent piece travels down the chute or passage 97 and drops upon an anvil 99, and then rolls upon the pivoted weigher 100 carried by the movable plate 89. If the coin is of the required weight the weigher 100 is swung downwardly by the coin into alignment with one entrance 101 to the common discharge passage 102, and the coin rolls into said passage 102 and drops into one of the pockets 57 through outlet 103. The nickel rolls down the passage 98 and drops upon the anvil 104, and then rolls upon the pivoted weigher 105 carried by the movable plate 89. The weigher then swings downwardly to discharge the coin through entrance 106 into the common passage 102 for delivery to the pockets 57. Coins, slugs or other devices which are too thick, or bent, or which cannot roll otherwise through the passages 97 or 98 because of the size thereof remain lodged

in the scavenger. Devices which roll onto the weighers 100 or 105 but are too light to depress the same remain on said weighers until the scavenger is actuated to release such defective 5 coins, slugs or other devices.

In case the device inserted in the apparatus to operate the vending machine lodges in the scavenger 86 no proper coin will be seated in a coin pocket 57 for releasing the detent 72, and 10 hence the machine cannot be operated to dispense the commodity.

In the present invention however the control mechanism 10 is designed as above described to allow a limited movement of the operating means 11 in a clockwise direction from each centered position and the return thereof to said position for actuating the scavenger 86. For this purpose the movable plate 89 of the scavenger is connected by a link 107 with the centering dog 50. The dog 20 50 is provided with a rearwardly extending arm 108 clearing the slug returning chute 109 located below the scavenger for receiving the coins, slugs and devices released therefrom for return to the operator. The movable plate 89 is also provided 25 with a normally extending arm 110, the link 107 being loosely connected at the ends thereof to said arms 108 and 110. The plate 89 is retained in closed position by the spring 111.

When a defective or improper coin or similar 30 device is inserted into the scavenger and remains therein, upon rotation of the knob 21 the dog 50 is cammed upwardly as shown in Fig. 5 to swing the plate 89 together with the weighers 100 and 105 outwardly to release any device lodged between the plates 89 and 90 or resting upon said 35 weighers. Any device released from the scavenger drops from the chute 109 into chutes 112 and 113 (Fig. 2) carried by the frame 17 for return to the operator through opening 114 in the 40 casing (Fig. 14). The movement of control 10 allowed for operating the scavenger is from the position shown in Fig. 4 to the position shown in Fig. 5 when the detent abutment 75 engages the contiguous step 43 of the ratchet 42 to prevent 45 further rotation. When the knob 21 is released the spring controlled dog 50 by a camming action returns the mechanism to the centered position illustrated at Fig. 4, and the scavenger is allowed to close.

50 In the present invention when cent pieces are inserted into the apparatus the detent 72 is elevated by the coin sufficiently to clear the contiguous step 43 of the ratchet 42 and to drop back upon the ratchet in the next position when the 55 coin passes the same. As the operating means is rotated step by step the drum pockets 14 are brought successively below the hopper 13 into position to be filled therefrom, and upon each step movement of the operating means the detent 72 60 strikes the radial end of a step 43 which jars the apparatus to facilitate and insure complete filling of the individual dispensing pockets 14 of the drum 12 as the same are brought successively into filling or loading position.

65 However, when the detent 72 is elevated by a coin of greater diameter to disengage the ratchet 42 to allow a complete revolution, said ratchet becomes inoperative to effect said jarring action as the pockets 14 move successively into filling position, and I therefore provide supplemental means 70 115 for interrupting the continuity of the rotation as the pockets 14 are brought successively into said position, which interruptions serve to jar the apparatus in each filling position of the pockets 14 75 to insure full quantity delivery of the commodity

from the several pockets during the revolution of the operating means.

As one example of such interrupting and jarring means, I preferably employ a disk 116 secured to the shaft section 23 at the rear for rotation therewith, and provided with an endless groove 117 upon the rear face thereof (Fig. 3) having formed therein a succession of shoulders 118 corresponding in number with the number of pockets and arranged in positions corresponding thereto as shown in Fig. 12. An arm 119 is freely pivoted at one end 120 to the rear wall of the casing 20 at the side thereof towards which the rotation takes place, extends horizontally towards said disk and is provided at its free end with a laterally extending pin 121 riding in said groove 117 at the uppermost point thereof. A stop 122 is provided to limit the downward movement of the arm 119.

The groove 117 comprises communicating arcuate sections or segments 123 in which the centers thereof are arranged equidistant apart about a circle concentric with the center of the shaft 23, the arcuate sections 123 being therefore eccentric relative to the axis of rotation, and the contiguous ends thereof being offset relative to each other to form the shoulders 118 each of which overlies the contiguous end 124 of the next succeeding arcuate section in the uppermost position of the shoulders.

When the detent 72 is released for operation of the rotor 12 through a complete revolution, the operator naturally rotates the knob 21 very rapidly, which might otherwise prevent complete filling of the pockets 14. With the structural arrangement above described upon such rotation the pin 121 in riding through the successive sections 123 strikes the successive abutments 118 which action momentarily interrupts the rotation and jars the apparatus to insure complete filling of the pockets as the same attain filling position. Upon such engagement of the pin 121 with a shoulder 118 a time element for filling is introduced of the duration required to allow the pin 121 to drop from the position shown in broken lines (Fig. 3) into the next succeeding segment 123 as shown in full lines in Fig. 3.

The operation of the coin controlled mechanism 10 and of the apparatus 11 released thereby for operation will be largely obvious from the foregoing description.

When a cent piece is inserted in the slot 93 it passes the test of the scavenger 86 and drops into one of the pockets 57. Upon rotation of the actuator 21, the cent piece is moved by the operating means into engagement with the pin 77 (Fig. 10) to lift the detent 72 out of engagement with the ratchet 42, the coin clearing said pin in time to allow the detent to drop back and lock the mechanism in the next succeeding position. During this operation the nose 71 of the detent 72 engages the abutment 85 of the disk member 67 to retain the same against movement with the operating means, the slip connection 80 releasing to allow such relative movement. 65 During this movement the drum 12 rotates one step to discharge a measured quantity of the commodity into the chute 38 for delivery to the purchaser through an opening 38a disposed at the front of the casing 20 (Fig. 14). The ratchet 70 42 and disk 67 then interlock in the next succeeding relative position.

When a nickel is inserted in the apparatus through slot 95, it also passes the test of the scavenger 86 and drops into one of the pockets 75

57. Upon rotation of the actuator 21, the coin elevates the detent 72 (Fig. 11) to a greater extent to clear the disk 67 and to drop upon the dwell 70 thereof as the coin clears the pin 11. 5
 5 Hence, the detent 72 remains disengaged from the ratchet 42 to allow a complete revolution of the rotor 12 and disk 67, the detent dropping into the clearance 69 of the disk 67 to engage the ratchet 42 at the end of the revolution for 10 locking the mechanism. During said revolution all of the drum pockets 14 are brought successively into discharging relation to the chute 38 for delivering five measured quantities of the commodity to the purchaser. By interrupting 15 the continuity of the rotation and imparting successive jars to the apparatus by the action of the means 115 full quantity delivery of goods to the purchaser is insured when the rotor is rapidly rotated through a succession of steps. 20
 20 The apparatus or mechanism embodying my said invention is responsive to coins of different values to release said mechanism for rotation of the delivery means in one direction through a single step or a succession of steps for 25 delivering one or more measured quantities of the commodity or goods corresponding to the value of the coin inserted, the apparatus resetting or resuming normal position after each operation, without regard to the value of the coin 30 inserted, ready for operation by the next coin, and requiring only a single revolution of the actuator 21 to deliver the maximum quantity of commodity.

Further, said coin controlled mechanism, functioning as above described, is adapted for controlling a scavenger or fraud preventing device to insure against malicious, surreptitious or other operation thereof by means of slugs, defective coins or other devices liable to clog, jam 40 or otherwise damage the mechanism or serving to obtain the delivery of goods without value received.

Having thus described my invention, what I claim and desire to secure by Letters Patent is:

45 1. A check controlled mechanism comprising rotatable operating means, means for locking said operating means in a succession of positions including a locking member actuated by a coin of given denomination to allow a movement of 50 said operating means from one position to the next, and a member having a releasable connection with said operating means for movement therewith and normally retained by said locking member against movement, said second named 55 member retaining said locking member when actuated by a coin of another denomination, disengaged from said locking means for movement of said operating means through a succession of positions.

60 2. A check controlled mechanism comprising rotatable operating means, means for locking said operating means in a succession of positions including a member actuated by coins of different denominations, and a member having a re- 65 leasable connection with said operating means and supporting said locking member disengaged for movement of the operating means through a succession of steps, said supporting member being released from said operating means by engagement with said locking member in the partially elevated positions thereof.

65 3. A check controlled mechanism comprising rotatable operating means, a locking element thereon having a plurality of locking positions, 70 a coaxial element having a releasable connection

with said operating means for movement therewith, and a detent coacting with said elements and controlled by coins of different denomination moved by said operating means into engagement with said detent, said detent being actuated by a coin of one denomination to release said operating means for movement thereof a step relative to said second named element from one locking position to the next and by a coin of another denomination for clearing said second 10 named element to be supported thereby in disengaged relation to the locking element for joint movement of said operating means and said second element through a succession of locking positions. 15

4. A check controlled mechanism comprising rotatable operating means having a multiple stepped ratchet thereon, a detent coacting with said ratchet, a member having a recess therein for receiving said detent and an elevated portion for supporting the same disengaged from said ratchet, said member being mounted coaxially with said operating means for allowing relative movement of said ratchet to position said recess in predetermined relation to each of the ratchet steps, means operative as each of said 20 positions are attained for releasably locking the coaxial parts together for joint movement, and means for carrying coins of different diameters 25 into engagement with said detent for actuating the same. 30

5. A check controlled mechanism comprising rotatable operating means, a locking element thereon having a plurality of locking positions, 35 a detent co-operating with said locking element, means for carrying coins of different diameters into engagement with said detent by the movement of said operating means, and a coaxial element having a slip connection with said operating means for movement therewith, said element having a recess therein normally receiving said detent and retained thereby against movement and serving to support said detent upon actuation thereof by a coin of greater diameter. 40

6. A check controlled mechanism comprising 45 rotatable operating means, a multiple stepped ratchet element thereon, a detent engageable with said element, an element associated with said operating means, said second element having a recess therein for receiving said detent to engage therewith and an elevated detent supporting portion, means for releasably interlocking said associated element to said operating means in the successive positions thereof, and means for carrying coins into engagement with said detent by 50 the movement of said operating means, said detent when actuated by a coin of a given denomination clearing said ratchet element to allow a step movement of said operating means relative to the associated element, and when actuated by a coin of another denomination clearing both of 55 said elements and riding upon said elevated portion to allow movement of said operating means with said associated element through a succession of steps. 60

7. A check controlled mechanism comprising 65 rotatable operating means, a locking element having a detent for locking said operating means in a succession of positions, a member having a releasable connection with said operating means, 70 said member having a reduced portion receiving said detent and a relatively elevated portion for supporting said detent in disengaged relation to said locking element, and means for carrying coins into engagement with said detent by the 75

movement of said operating means, said detent being actuated by a coin of a given diameter to allow a step movement of said operating means relative to said member, and by a coin of great 5 diameter to clear said member to ride thereon for movement of said operating means through a succession of steps.

8. Check controlled mechanism comprising rotatable operating means, a multiple stepped 10 ratchet thereon, a coaxial member having a recess therein and an elevated peripheral portion, said member and said ratchet being relatively movable to allow said recess to be brought into predetermined relation to the successive steps of 15 the ratchet, releasable means for locking said parts together in the several relative positions, a detent in engagement with said ratchet and received into the recess of said member to interengage therewith, and means for carrying coins 20 into engagement with said detent by the movement of said operating means, said detent being actuated by a coin of given diameter to release said ratchet to allow step movement of the operating means relative to said member, and to 25 bring the recess in said member into operative relation to the next succeeding step of the ratchet, and by a coin of greater diameter to clear said member to be supported by the peripheral

portion thereof, for movement of the operating means through a succession of steps.

9. A check controlled mechanism comprising rotatable operating means having coin receiving pockets thereon, a scavenger adapted to receive coins of different diameters for delivery to said pockets and including a member actuatable to release devices lodged therein, means for locking said operating means in a succession of positions including a locking member actuated by the coin of smaller diameter to allow a movement of said operating means from one position to the next, said locking means normally allowing a limited movement of said operating means in the direction of said locking member, ratchet means including a detent for preventing rotation of said operating means in the opposite direction, means for centering said operating means in the successive positions thereof, a connection between said centering means and the actuatable scavenger member, and a member having a releasable connection with said operating means for retaining said locking member when actuated by the coin of greater diameter disengaged from said locking means for movement of said operating means through a succession of positions.

FAIRFIELD W. HOBAN.
